AIR SWEPT BALL MILL

Walter L. Maxson, Milwaukee, Wis., John A. Fagnant, Salt Lake City, Utah, and Edward H. Baxa, Milwaukee, Wis., assignors to Allis-Chalmers Manufacturing Company, Milwaukee, Wis., a corporation of Delaware

Application September 6, 1943, Serial No. 501,372

7 Claims. (Cl. 241—47)

This invention relates to air swept ball mills. Air swept ball mills for grinding dry materials are well known in the art. It is also well known to provide a discharging chamber in such mills distinct from the grinding space proper.

An object of this invention is to provide a simple, improved discharge and classifying chamber for air swept ball mills, having a diaphragm and frusto-conical screen for separating and discharging fine and coarse materials.

It is a further object to improve the action of a frusto-conical screen in an air swept mill by fluting its external surface.

It is a still further object of this invention to divide an air swept ball mill discharge chamber into a material cascading part and an oversize discharging part and to provide means for deflecting cascaded oversize material into said oversize discharging section by use of a frusto-conical screen surrounding the main air current.

Other and still further objects may appear from the following description with reference to the accompanying drawing, in which:

Fig. 1 is a vertical longitudinal sectional view of a mill according to the invention; and

Fig. 2 is a cross-section on the line II—II of Fig. 1.

Like reference characters refer to similar parts throughout the several views of the drawing.

An air swept ball mill 1 has a feed end wall 2 with hollow trunnion 3 and a discharge end wall 4 with a hollow discharge trunnion 5. The mill is rotatably supported by trunnions 3 and 5 in bearings 6. A stationary air inlet hood 7 is rotatably sealed in known manner with trunnion 3. A raw material feeder 8 of known type extends through hood 7 and trunnion 2. A gaseous fluid and material conduit or offtake 9 makes a rotatable seal connection of suitable known type with discharge trunnion 5. Any known means of suitable type, not shown, are provided to draw a current of air or other elastic fluid through the mill 1 and conduit or offtake 9.

The interior of mill 1 is divided by a foraminous grid or screen 11 having a large central aperture 12 into a grinding space 13 and a discharge and classifying chamber 14.

Within the chamber 14 and connected with the grid 11 adjacent its central aperture 12 is a funnel-like, frusto-conical perforated screen 16 coaxial with the mill 1 with its smaller end forming a tubular liner 17 extending through the discharge trunnion 5. The portion of the liner extension 17 within the trunnion is imperforate, and is coaxially spaced from the inner surface of the

trunnion by a helical fin 18. An annular diaphragm 19 is peripherally secured within the space 14, in spaced relation to grid 11, end wall 4, and screen 16. Circumferentially spaced between the grid 11 and diaphragm 19 are a plurality of lifter members 21. The part of the constant discharge chamber 14 lying axially between grid 11 and diaphragm 19 may be referred to as a ground material receiving or cascading part, and the part lying axially between diaphragm 19 and end wall 4, which need not be provided with lifters, may be referred to as a coarse material or oversize discharging part. Outlets 22 provided in the mill shell between diaphragm 19 and end wall 4 provide an escape for material in the oversize discharging part, and may be connected by helical conduits 23 and openings 24 with the grinding space 13, preferably near the feed end 2. Material entering conduits 23 will be conveyed in a well known manner into grinding space 13 during rotation of the mill 1. The fin 18 is pitched to convey any settled material tending to lodge at the junction of trunnion 5 and offtake 9 into the oversize discharging part of constant discharge chamber 14.

As is plainly shown in Fig. 2, the frusto-conical part of funnel-like screen 16 has its external surface longitudinally fluted or provided with ridges 26 along elements of the surface. The perforations 27 of the screen may be arranged in rows between the ridges, and are preferably of increasing area toward the smaller end of the screen 16 for a reason to appear hereinafter.

In operation the mill is rotated clockwise as viewed in Fig. 2. A current of air is induced through the hood 7 and grinding space 13. A strong current of air will sweep through the central aperture 12 of grid 11 and will flow with increasing velocity through the funnel shaped screen 16 and the liner extension 17. Flow through the outer openings of the grid 11 and chamber 14 outside screen 16 will be negligible due to the greater obstruction to flow through limited orifices.

Material to be comminuted, such as rocks, ores, coal, etc., is fed through feeder 8 into the grinding space 13 which may contain a charge of steel balls or other known grinding media. The raw material being tumbled in the mill is comminuted by the well known action of ball mills. Some of the finest powdered material will be swept along with the current of air through grinding space 13. Other ground material will filter through the apertures of grid 11 into the ground material receiving part of chamber 14 and will be lifted and

cascaded by lifters 21 over the outer surface of funnel-like screen 16. The finer portion of this cascading material will pass in fine streams through the perforations 27 of screen 16 and be brought into intimate contact with the stream of air passing with increasing velocity through screen 16 and liner extension 17. The strong current of air will carry away substantially all ground material of sufficient fineness, coarser materials passing all the way through. Of the materials cascaded over screen 16 a portion, largely oversize, will be deflected through the central opening of diaphragm 19 by the incline of the screen surface. This coarser material will enter the annular oversize discharging part of chamber 14.

Any material too coarse to be carried all the way out of offtake 9 settling and tending to accumulate in the offtake at its seal with trunnion 5, will be conveyed into the oversize discharging portion of chamber 14. All material in the material discharging part of chamber 14 will be discharged into conduits 23 and returned to the grinding space 13.

The fluting of screen 16 tends to increase its capacity and aid classification by impeding travel of material circumferentially of the screen and promoting a longitudinal sliding of the material over the screen surface so that more of the material may be dispersed through the perforations 27 which are of greater area as the air velocity within the screen increases and the stream is able to carry more material. Coarse material tends to be more effectively deflected through the opening of diaphragm 19 due to this longitudinal sliding promoted by fluting the surface of screen 16.

While a particular embodiment of the invention has been shown and described in detail, it will be understood that the invention is intended to include such modifications and equivalents as may readily occur to a person skilled in the art, and is limited only by the scope of the appended claims.

It is claimed and desired to secure by Letters Patent:

1. A rotating air swept ball mill having a discharge end, a transverse discharge screen spaced from the discharge end thereof, separating said mill into a grinding chamber and a discharge chamber, a hollow discharge trunnion, a liner extending through said trunnion in coaxially spaced relation, and having a frusto-conical, perforated extension within said discharge chamber connected with said discharge screen, an annular diaphragm peripherally dividing said discharge chamber and having its inner border coaxial with and spaced from the surface of said frusto-conical extension, material lifting means in said discharge chamber between said annular diaphragm and said discharge screen, and means communicating with said discharge chamber adjacent the discharge end of said mill to return oversize from said discharge chamber to the grinding chamber of said mill.

2. In an air swept ball mill, a grid spaced from the discharge end of said mill, a central aperture in said grid, a discharge trunnion, a coaxial liner radially spaced within said discharge trunnion, a helical spacer on said liner extending between said liner and the inner surface of said trunnion, a perforated frusto-conical extension on said liner having its base secured to said grid adjacent the central opening thereof, an annular wall peripherally dividing the space between said grid and

the discharge end of said mill and having its central aperture spaced from said liner and said frusto-conical extension, material lifting means in the space between said grid and said annular wall, means for circulating elastic fluid through said trunnion liner and mill for carrying away finely ground product, and oversize discharge means connected with the space bounded by said liner, said annular wall and the discharge end and trunnion of said mill.

3. An air swept ball mill having a grinding space and a discharge trunnion, comprising a grid spaced from said discharge trunnion and having a central aperture, an annular wall peripherally dividing the space between said grid and said discharge trunnion, material lifting means between said grid and said wall, coaxial screening means connected with said grid and said trunnion, so constructed and arranged as to separate material showered externally thereon into fines passing within said coaxial screen and oversize deflected by said screen through the inner aperture of said annular wall, means between said wall and trunnion for returning said oversize to said grinding space, and means for circulating elastic fluid through the interior of said mill, screen, and trunnion for removing said fines.

4. In an air swept ball mill having a grinding space and a hollow discharge trunnion, a constant discharge chamber comprising an annular foraminous grid spaced from the discharge end of said mill, a frusto-conical screen in said chamber having its base secured in the central opening of said annular grid and its smaller end connected to a cylindrical liner in said hollow discharge trunnion, an annular diaphragm in said chamber secured to said mill periphery and having its inner opening spaced from the surface of said screen, and lifting means in said chamber for showering material passing said foraminous grid upon the external surface of said screen.

5. An air swept ball mill comprising a substantially horizontal drum rotating on its axis, a transverse discharge chamber in said drum, a frusto-conical screen within said chamber and coaxial with said drum, an annular transverse diaphragm in said chamber having its inner periphery radially spaced from and surrounding said screen adjacent the smaller end thereof, means in said chamber for showering ground material over the external surface of said screen, said screen deflecting oversize particles axially through the opening of said diaphragm.

6. A horizontal dry classifier for ball mills comprising a frusto-conical screen having a coaxial tubular extension at the smaller end thereof, means operatively connected with said screen for rotating said screen on its axis, means operatively connected with said tubular extension for causing a current of air axially through the interior of said screen and said tubular extension, an annular transverse wall having an opening surrounding said screen in radially spaced relation adjacent the smaller end thereof, and means for showering ground material transversely over the external frusto-conical screen surface of said screen, the frusto-conical surface of said screen being effective to deflect oversize ground material particles axially through said opening.

7. A horizontal dry classifier for granular materials comprising a perforated frusto-conical screen element mounted for rotation with its axis horizontal, the perforations in said screen increasing in total area of openings in successive

axial bands from the larger end to the smaller end means for showering granular materials to be separated transversely over the external surface of said screen element, and means operatively connected with said screen for causing a generally axial stream of gaseous fluid to flow through the interior of said screen element toward and outwardly through the smaller end, said screen dispersing ever larger quantities of fine granular materials passing through its per- 10

forations in the path of the stream of gaseous fluid through said screen as the velocity and hence the capacity of said stream of gaseous fluid to carry off such materials is increased due to the gradual constriction of the passage through the interior of said screen.
